US0D1104413S

(12) United States Design Patent (10) Patent No.: US D1,104,413 S
(45) Date of Patent: * Dec. 9, 2025

(54) CLOTHING

(71) Applicant: CONSITEX S.A., Stabio (CH)

(72) Inventor: Alessandro Sartori, Trivero (IT)

(73) Assignee: CONSITEX S.A., Stabio (CH)

() Term: 15 Years

(21) Appl. No.: 29/863,917

(22) Filed: Dec. 23, 2022

(30) Foreign Application Priority Data

Jun. 27, 2022 (EM) 009071533

(51) LOC (15) Cl. 02-02

(52) U.S. Cl.

USPC D2/853; D2/828; D2/999

(58) Field of Classification Search

USPC D2/717, 731, 749-755, 828, 829, 853,
D2/999

CPC A41B 1/00; A41B 1/08; A41B 2400/80;
A41B 2500/10; A41D 2500/10

See application file for complete search history.

(57) CLAIM

The ornamental design for a clothing as shown and described.

DESCRIPTION

The sole FIGURE is a perspective view of a clothing showing my new design.

The broken lines depict boundaries of the claimed design; the boundaries themselves form no part of the claimed design. The portions of background, environment and clothing illustrated outside of the broken lines are illustrated as faded and deemphasized and form no part of the claimed design.

1 Claim, 1 Drawing Sheet
